UNITED STATES PATENT OFFICE.

FRANK M. PIERCE, OF CHICAGO, ILLINOIS, ASSIGNOR TO PIERCE WRAPPING MACHINE COMPANY, A CORPORATION OF ILLINOIS.

FOLDER DEVICE FOR WRAPPING-MACHINES.

1,244,541.

Specification of Letters Patent. Patented Oct. 30, 1917.

Original application filed November 26, 1915, Serial No. 63,502. Divided and this application filed February 21, 1916. Serial No. 79,619.

To all whom it may concern:

Be it known that I, FRANK M. PIERCE, a citizen of the United States, and a resident of the city of Chicago, in the county of Cook and State of Illinois, have invented certain new and useful Improvements in Folder Devices for Wrapping-Machines; and I do hereby declare that the following is a full, clear, and exact description of the same, reference being had to the accompanying drawings, and to the numerals of reference marked thereon, which form a part of this specification.

This invention constitutes a division of my co-pending application for "double wrapper wrapping machines," filed November 26th, 1915, Serial No. 63,502.

This invention relates more particularly to an improved type of folder plate for use on the revolving shuttle of the wrapping machine through which the paper or wrapping material is drawn for application to an annular object such as a tire or coil of wire, whereby the material is folded and creased along each of its margins immediately prior to its application upon the article being wrapped.

It is an object therefore of this invention to provide a folder device pivotally and resiliently mounted upon a shuttle and used in conjunction with a tension mechanism through which the paper material is drawn prior to its introduction through the folder device whereby the opposite margins of the strip are folded as the same is applied upon the article.

It is an object therefore of this invention to construct an improved type of folder device mounted resiliently and in an angled position upon a revoluble shuttle to receive a strip of wrapping material drawn therethrough to fold the margins of the wrapping material as it is fed from the folder device to the article being wrapped.

It is also an object of this invention to construct a folder device constructed to receive a strip of full width admitted thereto and as said strip is passed therethrough acting to fold the margins thereof over so that the strip as applied to an article being

wrapped has its opposite edges folded inwardly beneath the strip, thus greatly reinforcing the wrapper applied to the article.

It is furthermore an important object of this invention to construct a resiliently and pivotally mounted folder device adapted to fold the opposite margins of a strip of wrapping material inwardly toward one another as the strip is drawn therethrough and used in combination with a tension device through which the strip is passed from the reel before passage through the folder device.

It is finally an object of this invention to construct a simple and improved type of folder device pivotally and resiliently mounted at an angle to the shuttle on which the device is mounted, whereby the strip of wrapping material passed through the folder device is drawn therefrom toward the point of application upon an article in a correct line of movement to obviate tearing or breaking of the strip.

The invention (in a preferred form) is illustrated in the drawings and hereinafter more fully described.

In the drawings:

Figure 1 is a front elevation of a wrapping machine provided with a revoluble shuttle equipped with a folder device embodying the principles of my invention.

Fig. 2 is an elevational view of the shuttle detached from the wrapping machine with the folder device mounted thereon.

Fig. 3 is a side view of the shuttle shown in Fig. 2.

Fig. 4 is a top plan view of the shuttle shown in Figs. 2 and 3.

Fig. 5 is an enlarged top plan view of the folder device detached from the shuttle.

Fig. 6 is a fragmentary detail section taken on line 6-6 of Fig. 2.

Fig. 7 is a rear elevational view of the folder device shown in Fig. 6.

Fig. 8 is an end view of the folder device at the exit end thereof.

Fig. 9 is a detail section taken on line 9-9 of Fig. 8.

Fig. 10 is a detail section taken on line 10-10 of Fig. 6.

Fig. 11 is a detail section taken on line 11—11 of Fig. 6.

Fig. 12 is a detail section taken on line 12—12 of Fig. 6.

5 As shown in the drawings:

The frame of the wrapping machine is denoted as a whole by the reference numeral 1, and suitably mounted therein to receive a wrapper applied thereto is an annular object 2, supported upon means which serve to revolve the object. Revolubly mounted in the wrapping machine and forming a part thereof, is a circular open gap revoluble shuttle 3, driven by suitable means 10 to revolve through the eye of the annular object 2. Mounted perpendicularly upon the front surface of the shuttle 3, is a paper reel 4, from which the strip of paper is led through a tension device consisting of a 15 plate 5, having a plurality of upright pins 6, thereon, around which the paper strip is led and from the tension device to and through the folder device from which it is drawn with its margins folded for application 20 around the article being wrapped. Said folder device consists of a flat plate 7, one end of which is of reduced width due to the provision of notches 8, therein, and with the other end of said plate curved and 25 bent around to afford a cylindrical portion 9. Another plate 10, is attached to and spaced from said plate 7, with the margins 11, of said plate 10, bent inwardly in a conical manner, so that the same converge 30 toward the reduced end of the plate 7, and with a portion 12, of said margins flattened and riveted flat against the surface of the plate 7, by rivets 13. As clearly shown in 35 Fig. 7, said plate 10, is provided with small slots 14, therein, through which access is had for riveting the two plates together and a large slot 15, is provided centrally of said plate 10, through which access may be had to the wrapping strip passing therewithin 40 45 as, for instance, in initially threading the end of the wrapping strip through the folder device. The cylindrical portion 9, of the folder device affords a means of attachment thereof upon the shuttle 3, and 50 for this purpose a bent pintle bolt having one portion 16, engaged perpendicularly through an aperture in the plate 5, and in the shuttle 3, is provided, secured therein by a nut 17, and the other or bent portion 55 18 of said bolt, inserted through the tubular portion 9, is at an angle to the surface of the shuttle, as clearly shown in Fig. 6, to give a tilt to the folding device. A flat headed retaining screw 19, is secured in the 60 upper end of the bent portion 18, of said pivot bolt whereby the folder device is retained thereon. As clearly shown in Fig. 2, a stop pin 20, is provided on said plate 5, to limit the outward swing of the folder device.

As clearly shown in Figs. 2, 3, and 4, another reel of wrapping material 21, is provided upon the shuttle 3, which may be of the same or different material from the reel 4, described, and the strip of material drawn therefrom is led through a tension device 22, and thence around a frustro-conical roll 23, to the article being wrapped.

The operation is as follows:

The strip of wrapping material 4, after being led from the reel through the tension device 5—6, is led around the rounded cylindrical extension 9, of the folder device and then threaded therethrough between the plates 7 and 10. The flaring portions 11, of the plate 10, which extend over the edges of the plate 7, serve to turn the margins of the strip of material 4, inwardly so that the same are folded beneath the strip as the same is applied upon the article. The construction of the folder device and the manner in which it is mounted, permits the same to readily adapt itself to practically any conditions of wrapping, that is, for articles of different size and as well takes care of the effects of high speeds of operation of the machine. The pivotal mounting of the folder device upon the inclined bolt 18, permits a certain movement of the folder device, and the tilt to the device, due to the angled position of the bolt, insures a proper feeding direction of the strip drawn through the device to the article. Furthermore, the curved portion of the plate 7, leading to the cylindrical portion 9, provides a somewhat resilient structure, so that a slight warping movement of the entire folder device may take place during a wrapping operation, so that the folder device readily accommodates itself to all conditions of wrapping, obviating any possibility of tearing the strip passing therethrough.

I am aware that various details of construction may be varied through a wide range without departing from the principles of this invention, and I therefore do not purpose limiting the patent granted otherwise than necessitated by the prior art.

I claim as my invention:

1. A folding device comprising a plate having one end formed into a cylindrical portion and the opposite end having oppositely disposed notches, a tapered plate having both edges flared to provide tapered conical members and flattened portions and means attaching the flattened portions to the first named plate.

2. A folder comprising a flat guide plate, a retaining plate having its edges flared to fold both sides of a strip of paper and then flattened to engage against and space the plates apart and means for rigidly attaching the flattened parts to the guide plate.

3. A folder comprising a guide plate formed to provide a cylindrical portion at

one end and notched at its opposite end, a retaining plate spaced therefrom, tapered conical folders at opposite edges of the plates having the outer ends flattened into said notches in the guide plate to provide a space equal to the space between said plates and means securing the plates together.

In testimony whereof I have hereunto subscribed my name in the presence of two subscribing witnesses.

FRANK M. PIERCE.
